UNITED STATES PATENT OFFICE

2,409,244

GLASS ELECTRIC HOT PLATE

John Bilan, Flint, Mich.

Original application November 5, 1943, Serial No. 509,063, now Patent No. 2,391,382, December 25, 1945. Divided and this application December 7, 1944, Serial No. 567,009

1 Claim. (Cl. 219—37)

1
This is the division of application on "burners," Serial No. 509,063, filed November 5, 1943, issued December 25, 1945, as Patent No. 2,391,382.

The present invention relates to burners and has for its main object the provision of a burner constructed entirely of glass within which electric wire coil is imbedded, so that when electricity is passed through the coil the entire glass is heated.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application, and in which like designating characters refer to corresponding parts throughout the several views;

Fig. 1 is a top elevational view of the burner; and

Fig. 2 is a cross-sectional view on line 2—2 of Fig. 1.

Referring to the present drawing there is shown therein a glass plate 10 which is provided on its bottom with a plurality of integrally formed and concentrically arranged annular ridges 11 which constitute the support for said plate 10. Imbedded within said glass plate 10 is electric wire coil 12, which is distributed throughout the plane of said plate 10, the two ends of said coil 12 extending beyond the perimeter of said plate 10 and bound into cord 13 which connects with a conventional switch 14 and from there connects with the usual socket (not shown) which in turn connects with a source of electricity.

The wire in coil 12 is made of the usual high resistance metal so that the same may heat to a great degree of temperature when electricity is

passed therethrough. Glass used in plate 10 is of the "pyrex" type, which does not crack when under the influence of a high temperature.

A plurality of transverse openings 15 is made in plate 10, in a spaced relation, transversely of the body of plate 10 and between the several strands of coil 12, for the purpose of providing draft through said plate 10.

When said plate 10 is placed upon a smooth surface, impervious to fire, and rested therein by its ridges 11, and electricity is open by switch 14, plate 10 will form a burner of high intensity upon which pots may be placed for boiling or heating the contents thereof.

The burner herein shown may be placed upon a metallic cylinder for supporting the same and for keeping the same out of contact with objects pervious to fire. When so supported one of the annular ridges 11 would either fit within the cylinder or be disposed outwardly therefrom, thereby maintaining the burner against lateral shifting upon the support.

While there is described herein a preferred embodiment of the present invention, it is nevertheless to be understood that minor changes may be made therein without departing from the spirit and scope of the invention as claimed.

What I claim as new is:

30 A burner comprising a glass plate, an electric wire coil of high resistance imbedded therein, said wire coil including a plurality of strands concentrically arranged, and a plurality of annular ridges concentrically arranged and extending from one face of said plate, said plate being **35** provided with a plurality of spaced openings transversely of the body of said plate, said openings being positioned within the several concentric areas defined by said strands.

JOHN BILAN.
